US0D1044502S

(12) **United States Design Patent** (10) Patent No.: **US D1,044,502 S**
de Leon Capozza et al. (45) Date of Patent: ** Oct. 1, 2024

(54) **BOTTLE**

(71) Applicant: **PepsiCo, Inc.**, Purchase, NY (US)

(72) Inventors: **Mirelle de Leon Capozza**, Newtown, CT (US); **Dmitriy Shmagin**, Palatine, IL (US); **Damien Z. Moyal**, Ypsilanti, MI (US); **John Siciliano**, Dexter, MI (US); **James M. Stelzer**, South Lyon, MI (US)

(73) Assignee: **PepsiCo, Inc.**, Purchase, NY (US)

(**) Term: **15 Years**

(21) Appl. No.: **29/897,077**

(22) Filed: **Jul. 11, 2023**

Related U.S. Application Data

(63) Continuation of application No. 29/859,082, filed on Nov. 7, 2022, now Pat. No. Des. 996,935, which is a continuation of application No. 29/794,419, filed on Jun. 11, 2021, now Pat. No. Des. 968,959.
